UNITED STATES PATENT OFFICE.

EDWARD R. IVES, OF BRIDGEPORT, CONNECTICUT.

DESIGN FOR A TOY-CAP EXPLoder.

SPECIFICATION forming part of Design No. 25,148, dated February 11, 1896.

Application filed December 21, 1895. Serial No. 572,931. Term of patent 7 years.

To all whom it may concern:

Be it known that I, EDWARD R. IVES, a citizen of the United States, residing at Bridgeport, in the county of Fairfield and State of Connecticut, have invented and produced a new and original Design for Toy-Cap Exploders; and I do declare the following to be a full, clear, and exact description of the same, reference being had to the accompanying drawing, forming a part thereof.

The figure represents a side elevation of a cap-exploder, illustrating my novel design.

The leading feature of my design consists in a foot-shaped body portion having toes at one end and having a defined line of demarcation from the heel forward to the instep, and a flat top of the ankle portion having a ring projection above it.

1 denotes the base of the foot portion having toes at one end.

3 is the ankle portion.

6 is the line of demarcation extending from about the middle of the heel forward and then up to the instep.

2 is the projection above the part 3 and 25 having an enlargement 4 with hole 5, forming substantially a ring.

Having thus described my invention, I claim—

The design for a toy-cap exploder substantially as shown and described. 30

In testimony whereof I affix my signature in presence of two witnesses.

EDWARD R. IVES.

Witnesses:

A. M. WOOSTER,
S. V. RICHARDSON.
